CLAIM

The ornamental design for a device for inducing microfluidic flow, as shown and described.

DESCRIPTION

FIG. 1 is a perspective view of a device for inducing microfluidic flow, showing our new design;
FIG. 2 is a top plan view thereof;
FIG. 3 is a bottom plan view thereof;
FIG. 4 is a front elevation view thereof;
FIG. 5 is a rear side elevation view thereof;
FIG. 6 is a left side elevation view thereof; and,
FIG. 7 is a right side elevation view thereof.
In the drawings, the broken lines depict portions of the device for inducing microfluidic flow that form no part of the claim.
